UNITED STATES PATENT OFFICE.

WILLIAM BOOTH PEARSALL, OF HAMPSTEAD, LONDON, ENGLAND,

DENTAL INSTRUMENT.

No. 882,711.

Specification of Letters Patent. Patented March 24, 1908.

Application filed August 6, 1906. Serial No. 329,457.

To all whom it may concern:

Be it known that I, WILLIAM BOOTH PEARSALL, a subject of the King of Great Britain and Ireland, residing at "Merrion," 5 97 Finchley road, borough of Hampstead, county of London, England, have invented certain new and useful Improvements in Instruments for Dentists' Use; and I do hereby declare the following to be a full, 10 clear, and exact description of the invention, such as will enable others skilled in the art to which it appertains to make and use the same.

This invention for an improved instrument for dentists' use relates to an instrument for pressing gold, platinum or alloy foils into cavities of teeth or casts made from such cavities from which to make matrices in which porcelain for repairing the natural 15 teeth by inlay is afterwards baked. These instruments are also intended for use in making plates for dentures with thin sheet-metal or casts of the mouth made of impression material, plaster of paris, Spence metal, 20 fusible metal, or other alloys cast in facsimile of the parts of the mouth to be fitted. The instruments will also be found useful for pressing amalgam fillings into cavities of the natural teeth, thus compelling this filling 25 material to adapt itself to the walls by rolling without the disturbance that takes place in the bedding of this material in the cavity by the usual method. When large cavities 30 have to be filled or large portions of the 35 crown of a tooth have to be restored their contours can be quickly rolled or modeled to a suitable shape so that the cusps of the opposing teeth of the other jaw can be fitted.

According to this invention, the instrument 40 consists of a stem or handle adapted to be held in the hand and inserted in the mouth, and a revolving head or roller mounted to revolve on the end of the stem and capable of being inserted in the cavities of 45 the teeth to press the foil into the tooth by rolling and thus cause it to conform or adapt itself to the shape of the cavity.

In carrying out the invention, a tapering metal rod or stem suitably curved at one end 50 has a roller mounted on its end, the surface

of the roller being either toothed, milled, or smooth, to suit different work. With the aid of this instrument foil one-thousandth of an inch in thickness can be accurately filled into the cavity and caused to conform to the 55 contour thereof without creasing or folding.

In the accompanying drawing Figures 1 and 2 are side views of dental instruments constructed according to this invention. Fig. 3 is an enlarged section taken through 60 the head of the instrument shown in Fig. 1, showing one method of mounting the revolving head; and Fig. 4 is an enlarged section of the head shown in Fig. 2.

The instrument consists of the handle or 65 stem *a* and the head *b* which is mounted coaxially with and adapted to revolve on the bent end of the stem. Instruments with revolving heads of various shapes and sizes 70 may be used according to the work to be done. As shown in Figs. 1 and 3, the instrument has a pear-shaped head, while that shown in Figs. 2 and 4 is substantially cylindrical. In attaching the head or roller *b* to the stem *a* the end *c* of the stem is reduced in 75 diameter, a shoulder *d* being formed for the head *b* to abut against. The end *c* may pass either partly or entirely through the head *b*. As shown in Figs. 3 and 4 the reduced end *c* passes through the revolving head and is ex- 80 panded at *f* to retain the head in position, the head being formed with a countersunk or similar recess *e*, which is closed by the riveted head *f*.

What I claim and desire to secure by Letters Patent is:—

A dental instrument of the character described consisting of a stem or handle having a bent end *c*, the latter being reduced in diameter and having a shoulder *d*, a head 90 rotatably mounted on the end *c* and abutting against the said shoulder, and an expanded head on the end *c* to hold the rotatable head in position on said end.

In testimony whereof I have affixed my 95 signature, in presence of two witnesses.

WILLIAM BOOTH PEARSALL.
